PLUMBING FIXTURE

Filed Feb. 16, 1925

INVENTOR:
WILLIAM HEWIG
BY
A. Ernest,
ATTORNEY.

UNITED STATES PATENT OFFICE.

WILLIAM HEWIG, OF LAKWOOD, OHIO, ASSIGNOR TO THE PARAGON BRASS MANUFACTURING COMPANY, OF CLEVELAND, OHIO, A CORPORATION OF OHIO.

PLUMBING FIXTURE.

Application filed February 16, 1925. Serial No. 9,433.

My invention relates to plumbing fixtures and particularly to a fixture provided with a soap tray.

The object of the invention is to provide a fixture of a certain type with a soap tray which may be easily attached and detached, which is simple in and economical of construction and which when in place will be firmly supported.

10 The said invention consists of means hereinafter fully described and particularly pointed out in the claims.

In the annexed drawing:

15 Figure 1 represents a front elevation of a fixture embodying my invention.

Fig. 2 represents a section in the plane indicated by line II—II in Fig. 1.

20 Fig. 3 represents a section in the plane indicated by line III—III, Fig. 2.

The illustrated embodiment of my invention includes a structure consisting of two valve controlled upright duct members 1—1, to which the supply pipes 2—2 may be connected; a transverse duct-member 3; the 25 common nozzle 4 for the said member 3, and the legs 5—5 by means of which the fixture may be secured to the upper edge portion 6 of a laundry tub 7 (shown in dotted lines).

30 The structure thus far described is of a well-known and accepted design.

The upper part of member 3 is however provided with an upwardly projecting integral lug 8 centrally placed thereon as shown in Fig. 2, which engages a hole 9 35 formed in a rearwardly extending horizontal wing 10 forming an integral part of a soap tray 11. The latter is provided with the usual peripheral flange 12 and the wing 10 forms an extension thereof substantially 40 parallel with the bottom 13 of the tray, Fig. 3.

An integral lug 14 is punched out of the

bottom of the tray and forms a continuation of the rear flange portion.

The hole 9 is so placed that when it engages the lug 8 and the tray is horizontal, the said lug will engage the front surface of the transverse member 3, in which position, Fig. 2, the rear flange portion will engage the front surfaces of the upright member 50 1—1, thus fixing the tray firmly in place.

Furthermore the width of the wing 10 is substantially equal to the distance between the members 1—1, Fig. 2, so that additional bearing for said wing is provided, thus still 55 further contributing to the firmness of the support for the tray.

To remove the tray it is merely necessary to lift it up so as to disengage the wing from the lug 8, as will be understood.

60 What I claim is:

1. In a plumbing fixture, the combination with two upright duct members connected by a transverse duct member; of a soap tray having its body portion in front of said upright members and a rearwardly extending wing located between same and attached to said transverse member.

2. In a plumbing fixture, the combination with two upright duct members connected by a transverse duct member, the latter being provided with an upwardly projecting lug; of a soap tray extending outwardly from said upright members and provided with a rearwardly extending wing located between said upright members and having an opening therethrough loosely engaging said lug; said tray being further provided with a downwardly extending lug at the rear of the body portion thereof and resting against 80 said transverse member.

Signed by me this tenth day of January, 1925.

WILLIAM HEWIG.
